UNITED STATES PATENT OFFICE.

LOUIS R. WHITE, OF BENNINGTON, VERMONT.

ELECTRICAL HEATING UNIT.

1,237,592.

Specification of Letters Patent. Patented Aug. 21, 1917.

Application filed October 21, 1915. Serial No. 57,037.

To all whom it may concern:

Be it known that I, LOUIS R. WHITE, a citizen of the United States, residing at Bennington, county of Bennington, and 5 State of Vermont, have invented a new and useful Improvement in Electrical Heating Units, of which the following is a specification.

My invention relates to a heating unit 10 comprising an embedded electrical conductor adapted to be heated by the passage of electric current therethrough. Such units, of various types of construction, are known in the art and extensively used for cooking 15 purposes in the home and factory, for heating rooms or other inclosures, and for various industrial purposes in the arts.

My invention relates more particularly 20 to an electrical heating unit for domestic purposes to be used in cooking, heating water and the like.

The object of my invention is to provide a heating unit of the class described which shall be capable of heating a given body of 25 material to a given temperature more quickly and with a less expenditure of energy than has hitherto been the case.

My invention will be better understood 30 by referring to the accompanying drawings in which Figure 1 represents an elevation, part section, of a unit of my invention as embodied in an ordinary "hot plate" for heating or cooking any material placed thereon; and Fig. 2 represents a plan view, 35 part section, of Fig. 1.

Referring to the drawings the heating unit proper, 1, is constituted as follows: A disk, 2, of rigid material, preferably iron, is provided with integrally attached 40 standing ribs, 3, of the same material. Preferably, these ribs are very narrow as compared with their height and are given the form of a continuous ribbon arranged as a spiral, beginning near the center of 45 the disk, 2, and ending near its periphery. An annular rib, 4, of the same character bounds the disk.

The spiral rib 3 is of uniform width except near the ends, which preferably taper 50 to a thin edge, and with the bounding rib, 4, act as stiffening devices to maintain the disk, 2, flat when subjected to heat in the normal operation of the device.

Resistance material adapted to have an 55 electric current passed through it is placed between the spaced convolutions of the

spiral rib 3. In the form of heating unit shown this material is a wire of some suitable metal or alloy wound as a helix, 5, and then laid spirally in the spiral channel 60 between the ribs. This resistance helix may be of bare wire and, in placing it in position in its channel, said channel is filled with a suitable cement which, when set, becomes extremely hard and capable of being 65 raised to high temperatures without deterioration or cracking. I find a suitable cement for this purpose is alundum, a material which contains from 92% to 100% of pure aluminum oxid and which can be 70 readily purchased upon the open market. This material is an electrical nonconductor, both when heated and when cool and, if the wire helix is suitably proportioned, may be inserted in the spiral channel with and 75 surrounding the wire helix so as to perfectly insulate, electrically, said helix from the rib, 3, and from the disk, 2.

The ends of the resistance helix may be joined to terminals, 6, 6, insulated from 80 the disk, 2, but suitably attached to said disk near the ends of the helix.

As shown in the drawing, the heating unit proper, as above described, is placed (a coating of heat resistant varnish or plastic cement may be used to assist in holding the unit in place) in a recess formed in a plate, 7, of any suitable refractory material. Preferably I prefer for this plate a material which is a good insulator, both for 85 heat and electricity, although the characteristic of electrical nonconductibility is of no particular importance. There are numerous compositions which satisfy my requirements and among the best, I find, are 90 those which are constituted substantially of asbestos fiber suitably compressed and united by a binder. The depth of the recess is, preferably, such that the top of the ribs, 3, and, 4, lies substantially below 95 the top of the plate; the entire unit is then covered, with the same cement as is used between the ribs, up to the level of the plate, 7.

The plate, 7, is mounted in the usual way upon a cylindrical casing 8, itself mounted 100 upon and above a base, 9. The terminals, 6, of the resistance helix are connected by conductors, 10, 10, to a suitable plug switch element, 11, by means of which connection 105 can be made to any convenient source of 110 electrical supply.

The casing, 8, is preferably filled with

mineral wool, or some equivalent heat insulating material.

In operation, the heat unit of my invention, as above described, may be made to absorb a very considerable amount of electrical energy and be raised thereby to a high temperature; indeed this temperature may be sufficiently high to bring the cement to a red heat. The temperature of the heating unit may be alternately raised to a high heat such as a red heat, as described, and current turned off and the unit allowed to cool to normal temperature as often as desired with impunity. The material will not crack under these circumstances, nor will the plate warp. This freedom from warping is probably largely due to the stiffness obtained by the use of the multiplicity of upstanding ribs.

A characteristic feature of this, my invention, is that the material of the helix is directly in contact with the body of the cement and the upper surface of the cement is directly in contact with the vessel containing the material to be heated. I have found from observation, in connection with numerous experiments, that the rate at which the temperature of the surface of a given heat unit or a hot plate is reached is greatly affected by the number of surfaces of separation between the material which actually carries the current and the surface of the hot plate. Thus a heat unit having an insulated wire embedded in enamel with the enamel itself in contact with the lower surface of an iron disk whose upper surface constitutes the effective heating surface of the hot plate, other things being equal, for a given expenditure of electrical energy will develop the maximum temperature at the upper surface of the hot plate much more slowly than will be the case at the upper surface of my hot plate, as above described, where the bare wire of the resistance material is directly in contact with the cement and the surface of the cement itself is the surface of the hot plate. This fact is of great importance to the economical operation of the hot plate for two reasons. In the first place, if a given maximum temperature is arrived at at the surface of one hot plate more quickly than at the surface of another it follows that the material heated by the first hot plate will attain its desired temperature more quickly than the same material heated by the second hot plate so that the current may be turned off more quickly in the one case than in the other. Furthermore, the heat lost by radiation will be very much less in the case of the first plate than in the case of the second plate, since the mounting of the heat unit will reach a substantially lesser

temperature in the case of the first unit than in the case of the second unit and, since the heat loss is proportional to the temperature gradient, it is clear that the loss of heat from the second unit will be much greater than that from the first unit.

While I have shown my improved heat unit as applied to an ordinary portable hot plate this has been done merely as a matter of convenience and it is clear that the same unit may be applied to electrical stoves having any desired number of hot plates as well as to electrical heating devices of various forms. Thus, for example, the principles of my invention may be embodied in electrical heaters having the form of receptacles or having the form of rods intended to be immersed in liquids or having any other of numerous possible forms.

While I prefer a spirally disposed rib, as described, a series of concentric ribs may be used instead, the resistance helices being also disposed concentrically between the ribs and connected together in series in any convenient way; or some other disposition of the ribs might be employed.

Furthermore, I find that it is possible, in some cases, to omit the ribs 3 on disk 2 and, in other cases to entirely dispense with both disk and ribs. And this of course, holds true for equivalent stiffening means which may be used in spiral forms of hot plates, or in water heaters or other electric heating devices. Whether disk alone, or disk and ribs, or any other stiffening device be used will depend upon size, shape and other physical characteristics of the particular heating unit under consideration as well as upon the uses to which it is to be put.

Having described my invention, I claim:

An electric heater comprising a support, a plate of insulating refractory material carried by said support and having a circular recess, a heating unit in said recess attached to the plate, said unit comprising a metallic plate having an integral spirally disposed upstanding rib, a body of alundum filling in between the convolutions of the rib and attached to said plate and rib with resistance material disposed in the spiral channel between the rib walls and covered by and directly in contact with the alundum, the free surface of the alundum being above the ribs and flush with the surface of the outer refractory plate.

In testimony whereof I have hereunto set my hand.

LOUIS R. WHITE.
